PRESS OPERATING DEVICE

Frank A. Doll, Detroit, Mich., assignor to Link Engineering Co., Detroit, Mich., a partnership composed of Herbert W. Link, Martha F. Link, and Frank A. Doll

Application January 17, 1944, Serial No. 518,523

3 Claims. (Cl. 60—54.5)

1

This invention relates to automatic presses and particularly to an automatic press of a combined hydraulic and air-operated type which produces rapid movement of the press bed to and from operating position.

When a rapid movement of the press bed was required of hydraulic presses supplied heretofore in the trade, it was the practice to supply a pump capable of delivering a large volume under high pressure which was expensive to manufacture and operate. For this reason, most of the presses were furnished without the quick bed operating feature so that a much smaller pump at materially reduced cost could be furnished.

It is one object of the present invention to provide an automatic press with a rapidly operating press bed, the movement of which is produced without the use of a hydraulic pump.

It is a further object of the invention to employ equipment which is actuated by air at a relatively low pressure for applying a high static pressure to the press bed when in operating position and for rapidly returning the bed to its initial position.

It is a still further object of the invention to apply air to a fluid in a reservoir for displacing the fluid and rapidly raising the bed of the press to operating position and after disconnecting the reservoir from the press to apply the air to a piston of a booster for materially increasing the pressure on the trapped fluid in the press for applying an increased pressure on the bed.

It is a still further object of the invention to include in the electric control circuit a time control device which controls the duration of operation of the press and which thereafter operates the control elements to produce the rapid return of the bed to its initial position.

Other objects and features of the novelty of the invention will be specifically pointed out or will become apparent when referring, for a better understanding of the invention, to the following description taken in conjunction with the accompanying drawing, wherein

Figure 1 is a broken sectional view of a press and the operating and control mechanism therefor, embodying features of this invention;

Figure 2 is a schematic diagram of the control circuit employed in connection with the structure illustrated in Fig. 1.

A press 10 of conventional form embodies a base 11 having therein a cylinder 12 in which a ram or piston 13 projects. The ram or piston is sealed within the cylinder by a packing gland 14 of conventional form. The piston supports a bed

2

15 guided on a plurality of standards 16 and urged downwardly to its lowermost inoperative position by springs 17 provided about the standard and disposed between the bed and the head 18 of the press. Die elements 19 and 20 are mounted on the head and bed respectively, being secured in position thereon by suitable bolts 21.

A tank 22 provides a reservoir for the oil 23, or other liquid employed for raising the bed 15. The tank is connected by a passageway 24 through a valve 25 to passageway 26 which is joined by a conductor 27 to the lower part of the cylinder 12. The passageway 26 is joined to a cylinder 28 in which a ram 29 is operated by a piston 31 in a double acting cylinder 32. The lower part of the cylinder 32 is joined to a conductor 33 which is also joined to the upper part of a cylinder 34 in which the valve 25 operates.

The conductor 33 is joined to a valve housing 35 in which valves 36 and 37 operate. The upper part of the cylinder 32 is joined to the valve housing 35 by a conductor 38 which is joined to a conductor 39 that is attached to the lower part of the cylinder 34. The head 41 of the tank 22 is joined by a conductor 42 to a passageway 43 in the valve housing 35. The passageway 43 is connected to atmosphere through a passageway 44 when the valve 36 has been moved to the left, as viewed in the figure. A supply of air, herein illustrated as provided by a pump 45 driven by a motor 46, is conducted through a pipe 47 and regulating valve 48 to a passageway 49 in the valve housing 35 communicating with both of the valves 36 and 37. The valve 36 is operated to the right against the tension of a spring 52 by a solenoid 53. The valve 37 is operated to the left against the tension of a spring 54 by a solenoid 55.

The platform 15 of the press 10 is provided with a boss 56 in which a switch operating rod 57 is adjustably secured by a screw 58. Substantially at the end of the upward movement of the bed 15 the rod 57 contacts a switch operating plunger 59 for operating a micro switch 61 for breaking the circuit through a contact 62 and completing the circuit through a contact 63. A time controlled relay 64 is mounted on the head 18 of the press, or at some other suitable location, for regulating the time of operation of the press. A starter switch 66 and a stop switch 65 are also mounted on the press at a point convenient to the operator.

When the starter switch 66 is pressed to closed position, relay contacts 68' are closed and are maintained closed through the energization of

the relay solenoid 68. At the same time current will flow through the pilot coil 69 of the time control unit 64. This results in the closing of the contacts 69' which will remain closed through the energization of the unit 64 for an adjustable time period independent of the continued energization of the coil 69, the adjustment being made through the setting of the lever 71. The closing of the contacts 68' also energizes the solenoid 53 which operates the valve 36 to the right against the tension of the spring 52. Air is conducted through the passageway 43 and conduit 42 into the tank 22 to apply a pressure of air to the top of the oil or other liquid 23. This forces some of the liquid out of the tank through the passageway 24 past the valve 25, which latter is moved to the bottom of the cylinder 34 by the passage of the air past the valve 37 and through the conduit 33. The liquid flows through the passageway 26 and conduit 27 to the bottom of the cylinder 12, which forces the piston or ram 13 upwardly until the die elements 19 and 29 are in engagement with each other. As the die elements 19 and 20 are about to come in contact with each other, the rod 57 engages the plunger 59 of the switch 61 to move the contact 62 to open position and to move the contact 63 into closed position.

The opening of the contact 62 de-energizes the solenoid 68 and opens the relay contacts 68', which deenergizes the solenoid 53 and permits the spring 52 to move the valve 36 to the left and exhaust the air in the tank 22 through the passageway 44. The closing of the contact 63 energizes the relay solenoid 74 which closes the contacts 74' and which in turn completes a circuit to the solenoid 55. The solenoid 55 operates the valve 37 to the left against the tension of the spring 54. This connects the conductor 33 to the atmosphere through a passageway 75 and connects the air from the passageway 43 to the passageway 38 which operates the valve 25 to close off the passageway 26 from the passageway 24, thus preventing a flow of liquid from the cylinder 12 to the tank 22.

The air also passes into the top portion of the cylinder 32 to move the piston 31 downwardly. This moves the ram 29 into the cylinder 28 and displaces the fluid therein, which build up a pressure in the cylinder 12, from the passageway 26, conduit 27 and the cylinder 28 to exert increased pressure upon the piston or ram 13 and increase the pressure between the die elements 19 and 20. The pressure that is created in this manner is proportional to the air pressure times the square of the diameter of the piston 31 divided by the square of the diameter of the ram 29. This ratio can be made anything desired to produce a desired amount of pressure between the die elements.

After this increased pressure has been applied for a predetermined time, the time control unit 64 operates to open the contacts 69' and its operation is interrupted. The opening of the contacts 69' de-energizes the relay coil 74 which opens the contacts 74' and de-energizes the solenoid 55. A spring 54 returns the valve 37 to the right and the air below the piston 25 passes through the conductor 39 to atmosphere through a passageway 78. Air from the passageway 43 passes into the conduit 33 into the lower portion of the cylinder 32 and the upper portion of cylinder 34 to move piston 31 upwardly and the valve 25 downwardly to permit the fluid in the cylinder 12 to flow into the tank 22. The springs

17 rapidly move the bed 15 of the press to its lowermost position.

The pressure of air produced by the pump may vary from 50 to 125 pounds so that the conventional air pressure equipment may be employed to actuate the press. With the automatic control feature herein provided, the structure is admirably adaptable for operating presses with heated dies for curing plastic material as the material is molded into predetermined form. The regulating valve in the air supply line maintains the pressures constant and the time relay controls the duration of application of the pressure so that the operations are accurately repeated. Other types of presses, such as welding presses, are similarly benefited by the use of the operating and control mechanism herein illustrated and described. With this mechanism, hand operated presses are readily converted to quick acting automatic presses with a minimum of expense.

What is claimed is:

1. The combination with a press having a bed movable into operative position, springs urging said bed toward inoperative position, a ram on said bed extending in a cylinder for moving said bed to operative position, a liquid in said cylinder, a reservoir for said liquid connected to said cylinder, a valve in said connection, a booster connected to said cylinder, an air-actuated piston operating said booster, a source of air under pressure, a solenoid valve for directing the air to the reservoir to move a portion of the liquid into the cylinder to advance the bed to operative position, a second solenoid valve, means when the bed is substantially in operative position for actuating said solenoid valves to operate the first said valve for cutting off the flow of liquid between the cylinder and reservoir, for connecting the air to the piston of the booster for increasing the pressure exerted by the bed and for removing the pressure of air from the reservoir, and a time control device which reverses the flow of air on the booster piston and operates the first said valve to connect the cylinder to the reservoir to permit the springs to quickly return the bed to its inoperative position.

2. The combination with a press having a bed moved by a ram in a cylinder to operative position, a reservoir for a liquid, a booster connected to the cylinder and solenoid operated control valves for a source of air, of a control circuit which includes a normally open starter switch, a relay shunting said switch, a normally closed switch in circuit with said relay, one of said solenoid valves also being in circuit with said relay and actuated to connect the air supply to the reservoir the liquid in which moves the bed to operative position, a normally open switch actuated to closed position when the press is moved to operative position, which movement also opens said normally closed switch and deenergizes said relay and first solenoid valve, a second solenoid valve actuated by the closing of said second switch to connect the air to the booster and for disconnecting the cylinder from the reservoir, and a third switch for opening the circuit to the second solenoid which reverses the flow of air on the booster and connects the cylinder to the reservoir to permit the press to quickly return to inoperative position.

3. The combination with a press having a bed moved by a ram in a cylinder to operative position, a reservoir for a liquid, a booster connected to the cylinder and solenoid operated control valves for a source of air, of a control circuit

which includes a normally open starter switch, a relay shunting said switch, a normally closed switch in circuit with said relay, one of said solenoid valves also being in circuit with said relay and actuated to connect the air supply to the reservoir the liquid of which moves the bed to operative position, a normally open switch actuated to closed position when the press is moved to operative position, which movement also opens said normally closed switch and deenergizes said relay and first solenoid valve, a second solenoid

valve actuated by the closing of said second switch to connect the air to the booster and for disconnecting the cylinder from the reservoir, a third switch for opening the circuit to the second solenoid which reverses the flow of air on the booster and connects the cylinder to the reservoir to permit the press to quickly return to inoperative position, and a timing device for operating said third switch for controlling the duration of operation of said press.
